UNITED STATES PATENT OFFICE

HERBERT A. BEEKMAN, OF CHICAGO, ILLINOIS, ASSIGNOR TO ZIM MANUFACTURING COMPANY, A CORPORATION OF ILLINOIS

VALVE-FACING TOOL

Application filed December 15, 1927. Serial No. 240,142.

The present invention has for its object to produce a simple and novel device by means of which a poppet valve may have its face accurately reamed by hand, although power may be utilized, if desired, to produce relative movements between the valve and the tool.

The various features of novelty whereby my invention is characterized will herein after be pointed out with particularity in the claim; but, for a full understanding of my invention and of its objects and advantages, reference may be had to the following detailed description taken in connection with 15 the accompanying drawing, wherein:

Figure 1 is a side view of a device embodying my invention in a preferred form; Fig. 2 is a section taken on line 2—2 of Fig. 1, showing in dotted lines a valve being inserted 20 in the device; Fig. 3 is a view similar to Fig. 2, showing the tool in cutting relation to the valve; and Fig. 4 is a top plan view of the device.

Referring to the drawing, 1 represents a 25 cylindrical cup-shaped member having a central downwardly projecting stem 2. Wings 3, 3 extending radially of the cup from opposite sides of the stem and joined to the bottom of the cup, are preferably provided to 30 stiffen the structure. The cup, with the stem and stiffening wings, preferably comprises a single integral casting. Around the mouth of the cup, that is constituting the upper annular edge, is a face 4 in the form of an 35 inverted frustum of a cone; the angle of the cone corresponding to the angle of the valve face to be reamed. There is a bore 5, coaxial with the conical surface, extending down through the bottom of the cup and through 40 the stem; this bore being of approximately the same diameter as the stems of the valve to be operated upon; and thus serving as a guide, when a valve is inserted in the device. The wall of the cup is thickened at one side 45 to produce a boss 6, lying partly within and partly without the cup. A non-circular hole 7 extends through the boss from bottom to top, at an angle to the vertical. A suitable cutting tool 8 is positioned in the hole in 50 the boss, being conveniently held in place

by means of a set screw 9. The cutting edge 10 of the tool lies parallel with the nearest element in the conical surface corresponding to the seat 4, but stands slightly above the same. This cutting edge is longer 55 than the width of the conical face in the cup and preferably projects somewhat beyond the latter, both inwardly and outwardly. The top face of the tool, indicated at 11, slants back from the cutting edge, as is usual with cutting tools of this general type.

When a valve, such as that shown at A in the drawing, is to be operated upon, its stem *a* is inserted through the guide opening 5 in the bottom of the cup and the stem far enough to permit the valve face to come to rest on the conical seat 4. The valve is then rotated, by means of a force applied to its stem, in a direction to permit the cutting 65 edge of the tool to ream the valve face. If the valve stem has an opening extending through the same near the lower end, a long pin, such as shown at B, may be inserted 70 through this opening to form a handle by 75 which the valve may be turned with one hand while the tool is held in the other hand.

It will be seen that the valve is accurately centered in the tool and, further, that the depth of cut may be nicely regulated since it 80 depends on the distance that the cutting edge projects above the conical surface. After the cutter has once been adjusted, it is impossible for it to dig into the valve face because the conical supporting seat prevents the valve 85 from being drawn down; and therefore, since the cutter is rigidly held, it can at no time cut into the valve face more deeply than the intended slight depth.

The diameter of the valve may vary, within limits, as long as the pitch of its face is the same as that of the conical seat in the tool, so that the use of the tool is not limited to valves of one diameter. The valve shown in the drawing is somewhat larger in diameter 95 than the smallest valve that can be faced, and it will be seen that if a considerably larger valve is to be operated upon, it will simply set higher up in the cup.

It will thus be seen that I have produced a 100

simple and novel valve facing device, consisting of a single casting, a cutter, and a screw for holding the cutter, by means of which the faces of valves may be quickly and accurately reamed by one not required to be a skilled mechanic.

While I have illustrated and described with particularity only a single preferred form of my invention, I do not desire to be limited to the exact structural details thus illustrated and described; but intend to cover all forms and arrangements which come within the definitions of my invention constituting the appended claim.

15 I claim:—

A valve-facing device comprising a cup-shaped member having a stem projecting downwardly from the bottom thereof, the upper edge of the cup being in the form of an inverted frustum of a cone, there being a bore coaxial with said cone extending through the bottom of said cup and through said stem, said cup being provided on one side with a boss, there being a hole 25 open at the top and at the bottom extending through the boss and the adjacent side of the cup, the hole intersecting said conical seat and having its long axis lying in a plane approximately parallel with the long axis of 30 the device and making an acute angle with a radial plane, and a cutting tool positioned in said hole and having at the upper end a cutting edge parallel with an element of the conical seat and lying slightly above the same.

35 In testimony whereof, I sign this specification.

HERBERT A. BERKMAN.
